UNITED STATES PATENT OFFICE

2,515,669

TAPE CONTAINER

William M. Scholl, Chicago, Ill.

Application February 5, 1945, Serial No. 576,197

5 Claims. (Cl. 206—52)

1

This invention relates to improvements in a tape container and a method of making the same, the tape container being highly desirable for the packaging of pressure-sensitive adhesive tape, paper tape in various colors, cloth tape, surgical tape, etc., although the invention may have other uses and purposes as will be apparent to one skilled in the art.

In the past, many and various types of tape containers have been developed. Many of these tape containers embodied a flanged spool around the barrel of which the tape was wound, and a cylindrical cover telescopically associated with the spool with some means on the cover for frictional engagement with the spool flanges. These formerly known devices were, however, objectionable in that in most cases one could not visualize the tape inside the container, could not determine the quantity of tape upon the spool without opening the container, and at the outset could not tell the character or color of the tape except by reliance upon matter printed on the outside of the container, in the event it was impossible to open the spool at the time a selection was made. Further, these formerly known devices frequently required the use of metal in order to provide a satisfactorily operating construction, and were in most instances objectionably costly to manufacture.

With the foregoing in mind, it is an important object of the instant invention to provide an economical and highly efficient tape holder within which the tape is visible to the eye at all times without requiring an opening of the container.

Another object of the invention is the provision of a tape container in which both the spool around the barrel of which the tape is wound as well as the cover for the spool are made of a plastic material.

Still another object of the invention resides in the provision of a tape container embodying a flanged spool, and a substantially cylindrical cover frictionally engageable over the flanges of the spool, which cover is made of substantially transparent plastic material.

Still a further object of the instant invention resides in the provision of a tape container embodying a molded plastic flanged spool, and a cover for telescopic association over the flanges of the spool, which cover is a section cut from a

2

transparent plastic tubing, with end formations provided on that section to enhance the frictional engagement of the cover with the flanges of spool.

It is a further feature of the instant invention to provide a tape container embodying a flanged spool, and a transparent plastic covering for the spool, the cover being substantially cylindrical, having outwardly upset end portions, and a row of spaced indentations formed in the cover adjacent each end thereof inside the upset portion, such indentations being of such character that the flanges of the spool may be snapped thereby, but which frictionally engage the outer faces of the spool flanges.

Still another feature of the instant invention is the provision of a new and novel method of making a tape container.

The advantages of the tape container of the character embodied in the instant invention are numerous. Such advantages include the clear visibility of the tape at all times so that when the tape is placed on sale on the counter of a store or the like, tape of the proper character and color may be quickly selected by the customer without the necessity of exposing the tape to handling by the prospective customer. Further, the amount of tape remaining upon the spool may be readily ascertained at any time without the necessity of opening the container or exposing the tape to air, and when the container is closed it is substantially air-tight, dust-proof, and easy to manipulate.

While some of the more salient features, characteristics and advantages of the instant invention have been above pointed out, others will become apparent from the following disclosures, taken in conjunction with the accompanying drawing, in which

Figure 1 is a view in elevation of a tape container embodying principles of the instant invention and made by the method embodied in the instant invention;

Figure 2 is an end view of the structure of Figure 1;

Figure 3 is an enlarged vertical sectional view, with parts in elevation, of the structure of Figures 1 and 2, taken substantially as indicated by the line III—III of Figure 2, looking in the direction of the arrows;

Figure 4 is an enlarged fragmentary eleva-

tional view illustrating a step in the making of a part of the tape container;

Figure 5 is a central vertical sectional view indicating a further step in the making of a part of the container; and

Figure 6 is a view similar in character to Figure 5 indicating the final steps in the making of the same part of the container, and illustrating that part in a finished condition.

As shown on the drawings:

In the illustrated embodiment of the instant invention there is shown a tape container embodying two parts, a spool around the barrel of which the tape may be wound, and a cover for telescopic association with that spool.

The spool, which is generally indicated by numeral 1, is preferably molded from a suitable plastic material, which plastic may be an opaque cellulose acetate, or another type of moldable plastic. A highly satisfactory process of forming the spool is the injection molding process.

The molded spool embodies a barrel 2 around which a quantity of tape may be wound as indicated at 3, and, in the illustrated instance, the spool is provided with a radially extending flange 4 at each end thereof. Of course, the tape 3 wound around the barrel of the spool may be of substantially any desired character, including pressure-sensitive adhesive tape, paper tape in various colors, cloth tape in various colors, mending tape, surgical tape, decorative tape, etc.

A cover 5 is provided for the spool 4. This cover is preferably made of a transparent plastic material and is provided with upset end portions 6-6. In the illustrated embodiment of the invention, a row of concavo-convex inwardly extending indentations 7 is provided around each end of the cover just inside the upset portion. As is best seen in Figure 3, the indentations are of such depth and size that the circumferential series of indentations adjacent each end of the cover are such that a flange of the container may be snapped or forced thereby, and the indentations will frictionally engage the outer side surface of the respective flange. At the same time, the cover itself is of such diameter as to establish a frictional engagement with the circumferential edges of the flanges.

The cover is telescopically associated with the flanges of the spool by a relative longitudinal movement of the respective parts, until the spool is seated so that the flanges are inside the circumferential series of indentations 7, as seen in Figure 3. The container is then in closed position and may be repeatedly opened and closed merely by forcing the spool out of the cover. The upsetting at the ends of the cover indicated by numeral 6 not only enhance the frictional engagement of the cover with the spool flanges, but also tend to reinforce the cover so that it will not split or crack after repeated usage. The indentations provide an effective medium of holding the spool within the cover against accidental dislodgment if the container is subjected to unexpected pressure, so that the container will not be accidentally opened.

When the container is closed, the tape is protected, the container being substantially airtight, and obviously dust-proof. Further, due to the transparency of the cover, the tape is visible at all times even to the most casual observer. Consequently, when purchased in the store the tape may be selected and the customer acquires the desired character and color of tape without

necessitating exposing the tape or handling the naked tape by the customer. At any time during possession of the container, the user may by the most casual glance ascertain approximately the amount of tape left in the container.

With reference to Figures 4, 5 and 6, it will be seen that my method of making the cover 5 includes the initial step of severing a section 8 of desired length from a tubing of transparent plastic material, preferably an extruded tubing. As seen in Figure 4, the tubing indicated by numeral 9 may be severed in any suitable manner along the dotted line 10 to provide a section 8 of desired length for the formation of one of the covers 5. The section 8 is then taken and with the aid of a heated die is outwardly upset at each end to provide the upset portions seen clearly in Figure 5. After that, the circumferential series of projections 7 may be pressed into the cover 5 by suitable heated die means to provide the resultant structure seen in Figure 6. The indentations, as stated above, are preferably provided just inside the upset portions 6-6.

It will be appreciated that the practice of this method is economical, and results in a sturdy, durable, and transparent cover for the container.

It will, of course, be understood that the various steps of the process as well as various details of construction may be varied through a wide range 30 without departing from the principles of this invention and it is, therefore, not the purpose to limit the patent granted hereon otherwise than necessitated by the scope of the appended claims.

I claim as my invention:

35 1. The method of making a tape container, including the steps of forming a flanged spool around the barrel of which tape may be wound, cutting a desired length from a tube of transparent plastic material of the proper diameter to pass over but frictionally engage the flanges of said spool, applying heat to the ends of said length of tubing to outwardly upset the ends thereof, and die-pressing spaced indentations around each end of said length of tubing inside the upset portions by which the spool flanges may snap when the spool is inserted in the tube.

2. The method of making a tape container, including molding a flanged spool of plastic material around the barrel of which spool tape may be wound, cutting a section of desired length from a tube of transparent plastic, upsetting the ends of said section, and pressing indentations adjacent the ends thereof in addition to said upsetting to enhance the frictional grip of the cover on the flanges of said spool to retain the spool within the cover against accidental dislodgement.

3. The method of making a generally cylindrical cover for a tape spool, including the steps of cutting a desired length from a tube of transparent plastic material of proper diameter to pass over but frictionally engage the spool, applying heat to the ends of said length of tubing, and upsetting the ends of the length of tubing to provide outwardly flared rims on both ends, and forming indentations in an annular series inside each upset end.

4. The method of making a generally cylindrical cover for a tape spool, including the steps of cutting a desired length from a tube of transparent plastic material of proper diameter to pass over but frictionally engage the spool, applying heat to the ends of said length of tubing, outwardly upsetting the ends of said length of tubing, and forming indentations in an annular series inside each upset end of the length of tubing.

5. A tape container including a flanged spool around the barrel of which tape may be wound, a cover in the general form of an open-ended cylinder in telescopic association with said spool, said cover being of substantially transparent plastic material and having its ends terminating in similar outwardly turned upset free edges, and formations in said cover engaging the spool flanges.
